UNITED STATES PATENT OFFICE.

HARRY C. H. WALSH, OF CHICAGO, ILLINOIS, ASSIGNOR TO WALSH PRESS & DIE CO.,
OF CHICAGO, ILLINOIS, A CORPORATION OF ILLINOIS.

DIE-PRESS.

1,146,978.

Specification of Letters Patent. Patented July 20, 1915.

Original application filed January 13, 1913. Serial No. 741,881. Divided and this application filed July 24, 1914. Serial No. 852,805.

To all whom it may concern:

Be it known that I, HARRY C. H. WALSH, a citizen of the United States, residing at Chicago, in the county of Cook and State 5 of Illinois, have invented certain new and useful Improvements in Die-Presses, of which the following is a specification.

This application is a division of an application previously filed by me January 13, 10 1913, Serial No. 741,881.

Heretofore it has been usual in constructing die presses of the character described to make the necessary adjustment between the reciprocating die head and the crank shaft 15 by adjusting the length of the pitman itself. This construction is subject to several disadvantages. In the first place, it necessitates making the pitman in two or three parts and in threading the several parts together, this resulting in a considerable reduction in the cross-sectional area of the members forming the pitman, while at the same time there are formed in these members abrupt changes in cross-sectional area 20 due to the screw threads which, it is well understood, seriously weaken the said parts. In addition to the above, a pitman composed of two or three parts is essentially heavier than one formed in a single piece, and its 25 inertia causes a large amount of wear and tear on the various parts of the press. In some cases, especially where a pitman is made of three parts threaded together, it is a difficult matter to keep the three parts 30 rigidly locked together; and, in any event, they must be made in the highest degree of accuracy and closeness of fit. My invention is designed to obviate the above difficulties, as will hereinafter appear.

40 This invention relates to improvements in die presses, and among its salient objects are, to provide a construction in which the adjustment of the reciprocating head relatively to the main shaft is effected in the 45 head itself, as distinguished from an adjustment of the length of the pitman proper; to provide improved means for conveniently and reliably unlocking the adjustable parts of the head and re-locking them in adjusted 50 position; and, in general, to provide an improved arrangement for connecting the reciprocating head with the rotating crank shaft of a die press.

The invention will be readily understood

from the following description, reference 55 being had to the accompanying drawings, in which—

Figure 1 is an end elevation of an assembled press embodying my improvements, the upper portion of the fly-wheel being broken 60 away to reduce the size of the drawing, and Fig. 2 is a section taken on the line 2—2 of Fig. 1.

Referring to the drawings, the main frame of the machine comprises two principal frame members, viz., a base or standard frame consisting of side members 1, 1 rigidly united with each other by means of suitable cross-bolts and spaced bars, and a tilting frame designated as a whole 2 and comprising 65 a pair of uprights 3, 3 integrally united with a cross-frame bar 4; the tilting frame being provided on each side with trunnions 70 which engage suitable bearing apertures in the upper ends of the standard members, as shown at 14', 14'. The lower ends of the members 2 are curved concentric with the transverse trunnion axis of the tilting frame and one of said members, the right-hand 75 one, is provided with worm gear teeth which intermesh with a worm shaft 6' journaled in suitable bracket-supports upon the inner side of a corresponding frame member 1. The end of the worm gear is square, as indicated at 7' to receive a wrench whereby 80 the upper frame may be tilted to any desired position of angularity, in an obvious manner.

At the upper end of each frame member 3 is formed a suitable journal block as 6, and in the journal bearings thus provided is 85 journaled a main shaft 7 which projects beyond the journal bearings some distance at each end; the left hand end extending through a brake-ring 8 and the right-hand 90 end carrying a fly-wheel 9.

In the standard 3 is arranged to reciprocate a die-head 10, formed of any suitable casting, and connected to the main shaft 7 by a pitman 12 in such a manner as to reciprocate on a revolution of the main shaft 100 in a well known manner. The die-head 10 is a casting or block arranged to slide in suitable guides on the standards 3, and provided in its upper portion with an internally threaded socket or bore adapted to receive 105 an axially disposed plug 11 provided with corresponding screw threads. The upper end of the plug 11 is provided with a socket-

head 11' adapted to receive a ball on the lower end of the pitman or connecting rod 12; the ball-and-socket joint thus formed being of ordinary construction. The socket-head 11' is provided with a series of spanner holes 11'' whereby it may be rotated to raise or lower it relatively to the die-head proper by reason of its screw-threaded connection therewith.

10 In order to lock the plug 11 in adjusted position in the die-head, an integral transversely extending boss 10' is formed on the front of the die-head, and this boss is bored to receive an eccentric locking bolt 39. The portion of this bolt next to the head fits the bore accurately, but the central portion is reduced, as indicated at 39' and is slightly eccentric. Between this eccentric portion 39' and the threaded side of the plug is interposed a block 39 which, by the action of the eccentric pin, is clamped against the plug and so serves to lock the latter against rotation. The check nut 40 is threaded on the reduced end of the locking bolt 39 so that when the locking bolt has been set the check nut can be turned up to lock it in this position. Both the head of the bolt 39 and the check nut are conveniently provided with spanner holes instead of being made with facets.

The main shaft 7 is provided with an intermediate crank or eccentric portion engaged by the upper end of the connecting rod or pitman, the latter being provided with the usual split journal, enabling it to be engaged with the crank.

From the foregoing it will be understood that the connecting rod or pitman is of fixed length and is a solid piece from the crank 40 of the main shaft to the ball-and-socket joint. The adjustment of the die-head to higher or lower position with respect to the crank is accomplished within the die-head

itself and not within the pitman, as has heretofore been common. The pitman being 45 a solid piece is not liable to breakage.

I claim as my invention—

1. In a die-press, the combination with a die-head, of a pitman of fixed length by which it is reciprocated, a bearing within 50 the die-head by means of which the pitman is pivotally connected thereto, and means by which said bearing may be axially adjusted with respect to said die-head.

2. In a die-press, the combination with a 55 die-head, of a pitman of fixed length by which it is reciprocated, an axially adjustable plug threaded within said die-head, said plug being provided with a pivotal connection to said pitman, and means by 60 which said plug may be locked at any desired adjustment.

3. In a die-press, the combination with a crank, a pitman, and a die-head, of a screw 65 threaded connection by which the distance between the pitman and the die-head is adjusted, of a laterally movable section of the screw threaded connection, and a cam or eccentric member by which said section is operated to lock or unlock said screw- 70 threaded connection.

4. In a die-press, a die-head, an axially adjustable member screwed into said die-head and providing a connection for a pitman, a transverse pin on said die-head and 75 providing an eccentric surface near the threaded portion of said die-head, and a movable section of such threaded portion, said movable section being so located as to be operated upon by said eccentric surface, 80 substantially as described.

HARRY C. H. WALSH.
